FUSE

Carl F. Nelson, Wharton, N. J., assignor to the
United States of America as represented by the
Secretary of War

Application September 22, 1943, Serial No. 503,412

2 Claims. (Cl. 102—70)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to a fuze of the barometric type for exploding shells, bombs or rockets at a selected or predetermined altitude.

An object of the invention is to provide a fuze which may be applied to a rocket, shell or bomb which will initiate the explosion of the explosive charge carried by the rocket, shell or bomb when it has reached a selected or predetermined position or level in its flight.

The fuze according to the invention depends for its actuation upon differences in atmospheric pressure prevailing at various levels above the surface of the earth. Before firing of the rocket or shell carrying the fuze according to the invention, or before releasing from aircraft a bomb provided with the fuze, the fuze may be set to become operative to initiate the explosion of the explosive charge of the bomb, shell or rocket when the latter has reached a selected or predetermined altitude or level in the atmosphere.

The manner in which the fuze is constructed is illustrated in the accompanying drawings and explained in the written description given below which refers by characters of reference to the said drawings. In the said drawings:

Figure 1 is a longitudinal section through the longitudinal axis of the fuze;

Figure 2 is a cross section on the line 2—2 of Figure 1;

Figure 3 is an enlarged section of part of the rack shown in Figure 1 with a part of the operating means or rod therefor shown in elevation;

Figure 4 is schematic representation, partly in perspective, illustrating the electric circuit used in the fuze and how it operates to cause the explosion of the explosive charge carried by the rocket, shell or bomb at the selected or predetermined level;

Figure 5 is a perspective view of the U-shaped spring shown in elevation in Figure 1; and

Figure 6 is an elevation of the means by which one of the legs of the spring is engaged with the aneroid means shown in Figure 1.

Referring now specifically to the accompanying drawings, in which the same characters of reference in the several views indicate the same part, the numeral 1 indicates the body portion of the rocket, shell or bomb which carries the explosive charge 2.

The base portion of the fuze comprises a circular member or adapter 3 which is attached by

screw threads to the body portion 4 of the fuze and by screw threads to the body portion 1 of the rocket, shell or bomb. The member or adapter 3 is formed with a cavity 5 of a suitable size to accommodate electric condenser 6 and electric primer 7. Electric condenser 6 and electric primer 7 may be secured in cavity 5 by any suitable holding means attached to adapter 3. In the drawings, such holding means are illustrated as spring fingers 8.

Condenser 6 serves as a source of electrical energy for producing a spark between the terminals 11 and 12 of the spark gap 14 in the electric primer 7. While a condenser is shown as the source of electric energy, it is to be understood that any other suitable source of electrical energy for the electric primer may be employed. For example, a small induction coil or Ruhmkorff coil and small dry cells may be used to produce the difference of potential necessary to cause sparks across spark gap 14 of the primer 7. When a condenser is employed it is charged in any suitable manner shortly before the fuze is put to use.

The adapter 3 is provided with a plate 15 of electrical insulation material which is sunk therein and secured thereto, on the upper side thereof. Secured to this plate is a bracket 16 having a base portion 17 and an overhanging head portion 18. Plate 15 serves to insulate the bracket 16 from the adapter 3.

Mounted on the base 17 of bracket 16 is a pair of guides 20 and 21 for the rack 22, which hold the rack upon base 11 while permitting it to slide longitudinally.

Head portion 18 of the bracket 16 and base portion 17 of said bracket are respectively provided with bearings 22 and 23 of insulating material for the shaft 24. Fixed to the shaft 24 is a pinion 25 which meshes with rack 22. Shaft 24, at its lower end, extends into an opening 26 in adapter 3, into which opening projects a spring electrical connection 27 for connecting the lower end of the shaft 24 with one side, or with one terminal, of the condenser 6, the other terminal of the condenser being connected by means of the insulated conductor 28 to the terminal 12 of the electric primer 7. The terminal 11 of the electric primer is grounded to the adapter 3 which in turn is grounded to body 4.

Shaft 24, at its upper end, passes through insulating bearing 22, and has a contact arm 30 fixed to its upper end by a pin or set screw 31.

The purpose of this arm is to close the electric

circuit which includes the condenser 6 and the primer 7, as more fully explained hereinafter.

An aneroid capsule or partially evacuated box, responsive to variations in atmospheric pressure, is indicated by the numeral 35. This capsule is secured by brazing or soldering to the head 36 of a bolt 37. The bolt 37 passes through an opening 38 (see Fig. 5) in U-spring 39 and through an opening in the vertical portion of bracket 16. Upon tightening the nut 40 on bolt 37 the spring 39 is clamped between the head 36 of the bolt 37 and the washer 42, and the pressure responsive member 35 assumes the position shown in Figure 1.

The pressure responsive member or capsule 35, on the side opposite the side to which the bolt is attached, carries engaging means 45 for the unsecured end of spring 39. Engaging means 45 may be soldered or brazed or otherwise suitably attached to the pressure responsive means 35. Engaging means 45 (see Fig. 6) is provided with a head portion 46 and a circular groove 45a adjacent thereto in order to provide a neck portion 45b.

Spring 39 (see Fig. 5) is provided with a slot 47 within which the neck 45b (see Fig. 6) of the spring engaging means 45 fits with a sliding fit. The shoulders provided by the groove 45a in engaging means 45 engage over the fingers 48 and 49 adjacent the slot 47, whereby the engaging means 45 and spring 39 may move outwardly together with a sliding fit of the fingers 48 and 49 in the groove 45a.

To the finger 48 of spring 39 is attached a rod 50 which extends from said finger into an opening 51 (see Fig. 3) in the body of the rack 22. The rod 50 fits slidably in the opening 51 so as to permit the rack 22 to be moved by it longitudinally between the guides 20 and 21 (see Fig. 2).

A nose 55 is fitted into and carried by the fuze body 4, and is held thereon by friction ring 56 and set screws pressing upon said friction ring, one of said set screws being indicated by the numeral 57 in Figure 1. Nose 55 may be rotated relative to body portion 4 and is held in the position to which it is rotated by the action of friction ring 56.

The nose portion is hollow as shown, and carries on its interior, near its bottom, a projection 58 (see Fig. 2) which lies in the path of the motion of the outer end of the arm 30.

From the foregoing it will be appreciated that the nose 55 may be rotated to position the projection 58 at any desired position relative to the initial or zero position of the arm 30. Graduations 59 are provided upon the nose 55, which in conjunction with the index 60 on the body portion 4, enables the position of projection 58 with respect to arm 30 to be set as desired. The graduations 59 represent altitudes at which the fuze will set off the explosive charge in the rocket, shell or bomb.

In order to maintain the air pressure within the fuze body and nose the same as the pressure of the air or atmospheric level through which the fuze passes in flight, the openings 65 in the nose 55 and openings 66 in the body 4 are provided. Openings 65 and 66 are so proportioned that the amount of air entering holes 65 is the same as the amount leaving from holes 66.

Operation: Nose 55 is rotated until the graduations 59 and index 60 indicate the altitude or

atmospheric level at which it is intended that the explosive charge 2 shall be exploded. For the purposes of explanation, it is assumed that the fuze has been applied to a rocket, and that the condenser 6 has been charged. As the rocket ascends, the pressure responsive capsule or means 35 expands. This expansion increases the distance between the legs of the U-spring 39, whereby the rod 50, as shown in Fig. 1, moves to the right. The movement of rod 50 is communicated to rack 22, which, being in engagement with pinion 25, causes the rotation of the latter and of shaft 24 and arm 30. When the rocket has reached the altitude or level for which the fuze has been set for exploding the charge 2, the outer end of the arm 30 makes contact with the projection or contact 58, thereby closing the circuit (see Fig. 4) including the condenser 6 and primer 7. When this circuit is closed, sparks pass across the spark gap 14 of the primer 7 and these sparks fire the primer. The primer upon being fired sets off the explosion of the explosive charge 2.

I claim:

1. In a fuze of the type described adapted for use with a projectile, a hollow body, an adapter constructed and arranged to secure said body in said projectile, the said adapter being provided with a cavity opening into said projectile, an electric primer in said cavity, a source of electrical energy operatively connected with said primer, barometric means responsive to variation in air pressure in said body, a U-shaped spring in said body, the said spring having one leg fixed and the other leg in engagement with said barometric means and responsive to differences in atmospheric pressure, a rack, means for communicating the motion of said last mentioned leg to said rack, a shaft, a pinion mounted on said shaft and meshing with said rack, whereby the said shaft is rotated upon movement of said rack, an arm fixed on said shaft for rotation therewith, a nose rotatably mounted on said body, a circumferential gauge on said nose calibrated with the pressure response of said barometric means, an electrical contact on said nose in the path of motion of said arm responsive to rotation of said nose to be positioned in a predetermined position relative to said arm and an electrical circuit including said arm, said contact, said electric primer, and said source of electric energy.

2. The structure of claim 1 in which insulating means are provided between the cavity in the adapter and the body of the fuze.

CARL F. NELSON.
